PRESS FOR SHEATHING CABLES

Walter Haendeler, Dusseldorf, Germany, assignor to
Schloemann Aktiengesellschaft, Dusseldorf, Germany

Application February 28, 1955, Serial No. 491,123

Claims priority, application Germany March 18, 1954

2 Claims. (Cl. 207—4)

This invention relates to a press for sheathing cables with aluminium, with a hollow mandrel, into which is pushed the front end of a tube surrounding the cable which is passing through the device and which is preferably being protected against heat by the said tube. The method of making these tubes as double-walled tubes and cooling them by water is known.

The bore of the point of the hollow mandrel is greater than the external diameter of that part of the cable which is not yet sheathed. The cable running into the device, and not yet sheathed, passes therefore with some play through the point of the mandrel so that it does not have to be directly in contact with the hot point of the mandrel. Contact between the cable and the hot point of the mandrel is particularly dangerous during those periods when the press is stopped because the cable insulation is then destroyed by the effect of the heat. It is the purpose of the present invention to prevent with certainty any contact between the cable and the mandrel and the invention employs for this purpose the protective tube mentioned above. The invention is based on a known type of press for sheathing cables with aluminium, where a cooled protective tube surrounding the cable is introduced in the mandrel of the press, the front end of the said tube being concentric with the mandrel, but at some distance from the said mandrel. It is necessary to maintain this distance while the cable is being sheathed with aluminium, because the mandrel of the press must be kept hot enough to avoid the cooling of the aluminium within the area of the mandrel during the stopping intervals of the press to a temperature which would render the continuation of the pressing process impossible. But this temperature of the point of the mandrel represents a danger for the insulation of the cable.

According to this invention the front end of the protective tube has a bore which is smaller than the bore of the point of the mandrel. The part of the cable which is not yet sheathed is passed through the said tube in such a way that it is never directly in contact with or even in the immediate neighbourhood of the hot point of the mandrel.

It is known that in lead presses the protective tube is tapered at the front and the conical surface is placed against the hollow conical internal surface of the mandrel, so that the mandrel is cooled by the cooled protective tube. In this case the protective tube is under the action of a force, for instance the pressure of a spring, which pushes the tube into the mandrel. Thus the front end of the protective tube is forced to make contact over a wide internal surface with the mandrel, and also the concentric position of the protective tube with respect to the mandrel is ensured. Since also in the case of the press of the present invention it is aimed to place the protective tube in a concentric position, while on the other hand the cooling of the mandrel, by the protective tube is to be prevented, the surface of con-

2

tact between the mandrel and the protective tube is kept as small as possible according to the invention. This is effected as follows: When the bore of the mandrel has the shape of a hollow cone, or the protective tube is externally conical, one of these two conical surfaces is provided with small contact surfaces, for instance lugs or other stops, against which the other conical surface bears.

In order that the invention may be clearly understood and readily carried into effect, the same will now be described more fully with reference to the accompanying drawings, in which:

Figure 1 is the general arrangement of a mandrel with a protective tube according to the invention; and

Figure 2 shows on a larger scale the position of the front end of the tube with respect to the point of the mandrel.

The mandrel 1 is inserted into the mandrel holder 2, which in its turn is held by a bush 3 screwed into the press body 4. The front end 5 of the protective tube 7 is pushed into the mandrel 1. The protective tube is designed as a cooling pipe. The cooling water runs into the pipe at its rear end at 8 and leaves the pipe at 9, in a known manner. The cable which is to be sheathed is inserted at 10 and leaves the apparatus at the front end 5 of the protective tube. As shown in Figure 2, the point of the mandrel 1 faces a die 11; between these parts a sheath-forming gap 12 is arranged. The material which is to be pressed and which is fed in the direction of the arrow 13 forms the sheath 14 round the cable 15. As shown in the drawing, the bore 1a of the point of the mandrel 1 is a little larger than the bore 5a of the front end 5 of the protective tube 7, so that the cable, when it makes contact with the front end of the tube, just avoids touching the internal surface of the point of the mandrel, which may be heated to a high temperature due, for instance, to the high temperature of the aluminium that is being extruded. The bore 1a of the point of the mandrel has an internally frusto-conical surface at 1b and may have for instance, a vertex angle of 30°, so that the generatrix of the frusto-conical surface 1b in the section makes an angle of 15° with the cable axis. The front end 5 of the tube 7 is also tapered and is with its four stops 16 concentric with the hollow frusto-conical surface 1b. The springs 17 apply a pressure at the rear end of the protective tube 7 and tend to push it constantly forward, as shown in Figure 1. The accurate concentric position of the tube in the mandrel can also be achieved by ensuring that the tapered end of the protective tube makes contact with

50 a ring of stops at about the position 1c, which project inwards from the internal conical bore of the mandrel. The aforementioned stops 16 projecting outwards from the protective tube would not then be required. If preferred, the ring of stops 1c may be replaced by a continuous internal annular shoulder on the mandrel. The contact surfaces of the stops 1c or of the shoulder substituted for them would have a conical curvature, so as to bear smoothly upon the conical surface of the protective tube, and it would not then be essential for the internal surface of the mandrel itself to be conical.

The vertex angle of the cone of which the contact surfaces form parts must be greater than the angle of friction between the materials of which the mandrel and the protective tube are composed. By the "angle of friction" is meant that angle the tangent of which is equal to the coefficient of friction. In the case of a body resting on an inclined plane, it is the maximum angle of inclination of the plane at which the body could rest without slipping down. If the angle between the surfaces of contact on opposite sides of the axis, or in other words the vertex angle of which the surfaces of

contact form parts, is greater than the angle of friction, any increased inward radial pressure between the surfaces, occasioned for example by the mandrel contracting owing to a fall of temperature, would push back the protective tube 7 against the thrust of the springs 17, thus maintaining the correct co-axial relationship between the protective tube and the mandrel.

The exact angle of friction between the internally frusto-conical surface 1b of the mandrel 1 and the contact surfaces of the stops 16, or between the conical surface of the front end 5 of the protective tube 7 and the stops 1c or the shoulder substituted for them, would of course depend upon the materials employed, the surface finish and the temperature, but its possible range of values would be known or could be ascertained for any particular case, and in designing the press the angle in question must be made greater than the maximum value of the angle of friction. The above-mentioned angle of 30 degrees between contact surfaces on opposite sides of the axis, or in other words of 15 degrees on each side of the axis, is believed to be quite a safe value to adopt.

I claim:

1. A press for sheathing insulated electric cables with aluminum, the extrusion temperature of which would be dangerous to the insulation of the cable, comprising a hollow mandrel internally tapered toward its front end, an axially movable protective tube within and spaced from the internal wall of the mandrel and through which the cable to be sheathed is fed to the front end of the mandrel of the press, means for cooling the protective tube, the internal diameter of the front end of the protective tube being smaller than the bore of the front end of the mandrel, and an annular array of stops hav-

ing small areas of contact extending between the internal tapered wall of the mandrel and the external wall of the tube adjacent its front end for maintaining the front end of the protective tube coaxial with and rearwardly of the front end of the mandrel with a suitable gap between the tube and the mandrel, whereby said small areas of contact minimize heat transfer between said mandrel and said tube.

2. A press for sheathing insulated electric cables as claimed in claim 1, the front end of the protective tube being externally frusto-conical, and the press further comprising resilient means urging the tube toward the front end of the mandrel.
